UNITED STATES PATENT OFFICE.

HENRY BARRATT, OF YORK, PENNSYLVANIA, ASSIGNOR OF ONE-HALF TO
JACOB O. MILLER, OF SAME PLACE.

CAR-BRAKE.

SPECIFICATION forming part of Letters Patent No. 288,398, dated November 13, 1883.

Application filed September 1, 1883. (No model.)

To all whom it may concern:

Be it known that I, HENRY BARRATT, a citizen of the United States, and a resident of York, county of York, and State of Pennsylvania, have invented certain new and useful 55 Improvements in Car-Brakes, of which the following is a specification.

My invention relates to that class of car-brakes in which the pressure of air, steam, or 10 other fluid is made the means of operating the brake, and has for its object to supply each car with means of applying the brake independent of the usual connection to the locomotive or other source of power; and to this 15 end my invention consists in locating upon a car auxiliary operating means connected directly with the main tube of the ordinary brake apparatus, whereby the brake may be operated by either the main or auxiliary source 20 of power, or by both at the same time.

The invention is designed more particularly as an adjunct to and an improvement upon the brake shown and described in my patent numbered 283,368, and dated August 21, 1883, 25 although it may be applied to any brake belonging to the class mentioned.

In the drawings, Figure 1 is a side view of a part of a car, showing my improvement; and Fig. 2 is a modification.

30 In order to more particularly describe my present invention, I have shown it as applied to a brake similar to the one shown in my patent above referred to.

The car-body is supported upon the usual 35 trucks, one of which is shown in the drawings, having a frame of the usual construction. To this frame is attached a central cross-beam, A, from which the brake bars or beams D are suspended by links a.

40 The shoes b are pivoted to the beam, so as to bear against the treads of the wheel C. To the cross-beam A is attached one or more cylinders, E, each provided with two pistons, i, having rods extending to the opposite ends of the cylinder, and provided at the extremities with disks or heads e, arranged opposite the inner sides of the brake-beams D. At the center of each cylinder is attached a tube, F, opening into the cylinder and connected by 45 means of a flexible pipe to the tube G, which extends throughout the length of the car, and

is provided with the usual flexible connections to join the car with another or to the locomotive, upon which are located the means for supplying air, steam, water, or other fluid under pressure, suitable cocks being provided, whereby the engineer or other person may transmit the pressure of the fluid at will to the cylinders E, and operate the brakes. When the pressure is brought upon the fluid in the 55 cylinder, the pistons i will be forced outward and the brake-beams D will be carried toward the wheels until the shoes are pressed firmly against the latter, in which condition they will remain until the pressure is removed, when 60 the weight of the beams and appurtenances will carry the shoes away from the wheels and bring the pistons together. Such is the usual 65 operation of the class of brakes referred to in my application previously named.

70 It sometimes becomes necessary to detach the car from the train or locomotive carrying the means for controlling the brake; or the car may become accidentally detached. It is then necessary to have some ready and accessible means 75 whereby the brakes may be applied by persons upon the detached car. It has been usual to provide cars having the automatic brake with the common hand-wheel, brake-levers, and connections, whereby the car may be controlled. In place of this I have substituted means upon each car for producing pressure 80 upon the air, water, or other fluid, and have connected the same to the main pipe G of the 85 brake, so that in case the car is detached, as above mentioned, or the source of supply is cut off, the requisite pressure may be quickly and easily produced to operate the brakes and control the movement of the car by persons on the car itself. As illustrative 90 of my invention, I have shown an ordinary air-pump, P, having the usual inlet and outlet valves and operating-piston and handle, one of the valves being connected with the main pipe G. This pump may be located in 95 any convenient and accessible part of the car, and may be of any ordinary and well-known construction. From this arrangement it will be seen that in case of accident by the breakage of connections or otherwise, ready means 100 are furnished for controlling the car.

The tube G may be provided with proper

stop-cocks for closing the openings thereof, which may be operated automatically or by hand.

In case the vacuum-brake is used, the pump 5 P and connections would be so arranged as to exhaust the air in the cylinder, instead of forcing it thereinto.

Instead of a reciprocating pump, other forms may be used—as, for instance, a rotary pump—10 and this may be connected by any suitable means with one of the car-axles in such a manner that the inertia of the car will drive the pump and produce the pressure required to operate the brake for stopping the car. I 15 have indicated a belt passing over a pulley on the axle and another on the pump; but of course gears or any other suitable connection may be used.

From the foregoing it is evident that many 20 modifications of my invention may be made without departing from the principle thereof.

I am aware of Patent No. 184,507, November 21, 1876, and do not claim anything claimed therein.

What I claim is—

1. The combination, with the main conducting-tube of a fluid-pressure brake, connected to the usual source of power upon the locomotive, of a pump located upon the car and connected directly to said tube, whereby the 30 brake may be operated by either the main or auxiliary source of power, or by both at the same time, substantially as described.

2. The combination, with the cylinders E, provided with the pistons carrying brake-shoes, of the main pipe G, and flexible connections between the same and the cylinder E, and the auxiliary pump P, connected directly to the tube G, whereby the brake-shoes may be operated directly by the main and auxiliary source of power, substantially as described. 35 40

In testimony whereof I have signed my name to this specification in the presence of two subscribing witnesses.

HENRY BARRATT.
